UNITED STATES PATENT OFFICE.

LOUISE H. BREWSTER, OF LEXINGTON, MASSACHUSETTS.

DESIGN FOR A WOVEN FABRIC OR SIMILAR ARTICLE.

Application filed October 4, 1922. Serial No. 3,883. Term of patent 7 years.

To all whom it may concern:

Be it known that I, LOUISE H. BREWSTER, a citizen of the United States, residing at Lexington, in the county of Middlesex and State of Massachusetts, have invented a new, original, and ornamental Design for Woven Fabric or Similar Article, of which the following is a specification, reference being had to the accompanying drawing, forming part hereof.

The drawing shows my design applied to a piece of woven fabric, and such design may be repeated indefinitely, according to the length of the piece of fabric.

I claim:

The ornamental design for woven fabric or similar article, as shown.

LOUISE H. BREWSTER.
